United States Patent Office

Des. 220,178
Patented Mar. 16, 1971

220,178

CENTRIFUGE

Richard W. Lanigan, Arlington Heights, Ill., assignor to
American Hospital Supply Corporation, Evanston, Ill.

Filed Oct. 9, 1969, Ser. No. 19,486

Term of patent 14 years

Int. Cl. D24—02

U.S. Cl. D16—2

FIG. 1

FIG. 2

FIG. 3

FIG. 4

FIG. 5

FIG. 1 is a perspective view of a centrifuge embodying the design;

FIG. 2 is a front elevational view;

FIG. 3 is a top plan view;

FIGS. 4 and 5 are side elevational views.

The undisclosed rear side is plane and unornamented. I claim:

The ornamental design for a centrifuge, substantially as shown and described.
